UNITED STATES PATENT OFFICE.

CLARENCE W. COURT, OF CHICAGO, ILLINOIS, ASSIGNOR TO WALTER P. MURPHY, OF NEW YORK, N. Y.

GONDOLA CAR OF THE DROP-END-GATE TYPE.

1,366,362.

Specification of Letters Patent. Patented Jan. 25, 1921.

Original application filed August 1, 1917, Serial No. 183,877, (now Patent No. 1,268,547, dated June 4, 1918.) Divided and this application filed April 24, 1918. Serial No. 230,396.

To all whom it may concern:

Be it known that I, CLARENCE W. COURT, a citizen of the United States, residing at Chicago, in the county of Cook and State 5 of Illinois, have invented certain new and useful Improvements in Gondola Cars of the Drop-End-Gate Type, of which the following is a specification.

My invention relates to a gondola car of 10 the drop end gate type, and the primary objects of the invention are to provide a drop end gate of novel construction composed in part of wood and part of steel, together with a novel form of hinge for use in connection with said gate.

The invention consists of the new and improved constructions, arrangements and devices to be hereinafter described and claimed for carrying out the above stated 20 objects and such other incidental objects as will appear from the following description.

The invention is illustrated, in a preferred embodiment, in the accompanying drawings 25 wherein—

Figure 1 is an end elevation of the superstructure of a drop end gondola car showing an end gate constructed in accordance with my invention.

Fig. 2 is a vertical section on line 2—2 of Fig. 1.

Fig. 3 is a horizontal section on line 3—3 of Fig. 1, with the flooring broken away to show one of the hinges of the end 35 gate, and

Fig. 4 is an enlarged fragmentary vertical sectional view to illustrate particularly the construction of the hinge, this view showing in full lines the gate in its 40 folded down position and in dotted lines the gate in the upright position.

Like characters of reference designate like parts in the several figures of the drawings.

Referring to the drawings, the side walls of the car are shown at 10, 10, the end sill at 11, and the floor of the car at 12. Associated with the end sill is a plate 13 which extends across the car from side to side and 50 is formed with an upstanding flange 14 providing an abutment for the lower edge of the end gate. Secured along the vertical edges of the side walls 10 are angle strips

15, 16 which, besides reinforcing the side walls, provide abutments 17 for the vertical 55 edges of the end gate.

The end gate is constructed as follows: 18 is a sheet of steel having pressed therein a plurality of preferably horizontal corrugations 19. The edges of the sheet are reinforced by angular reinforcing elements. For example, the vertical edges of the sheet are bent over to form flanges 20 while structural steel elements 21, 22, preferably channel members as shown, are riveted to the 60 upper and lower edges of the sheet. Filler strips 23 are arranged in two of the corrugations and to these strips are secured, by bolts 24, a series of boards 25 which are arranged at substantially right angles to the 65 corrugations. 26 are strips for the heads of bolts 24. The boards 25 are cut away at their ends so as to fit within the flanges 27, 28 of the reinforcing elements 21, 22. The unitary panel thus formed is extremely 70 strong and rigid, due to the fact that the boards cross the corrugations and because of the other details of construction just described. The boards provide a wooden lining 75 for the steel part of the structure which is desirable under some circumstances.

The end gate is hinged to the under frame of the car, preferably to the draft sills 29 by a pair of hinges constructed preferably as follows: 30 is an eye secured to the lower 85 inner edge of the gate, preferably by riveting its extremities to the channel member 22. This eye projects downwardly and inwardly at right angles to the plane of the inner face of the end gate and is engaged 90 by a link 31 with a staple 32 riveted to a plate 33 which lies upon and is secured to the draft sills 29. Both hinges may be constructed as above described and to make place for them the flooring is cut away as 95 indicated at 34.

It will be understood that a car of this type is used for two kinds of service. When the gate is in upright position the car is capable of carrying bulk freight, such 100 as coal, sand, and the like. By folding the gates down on the floor the car is effectively a flat car and may be used for transportation of pipe, rail, structural iron, beams, and other freight of this sort. The nature 105 of the articles transported under these con-

ditions, makes it imperative that the gate should be very strong. When carrying bulk freight a strong and rigid end gate is also essential, otherwise the load against it will 5 cause it to bulge.

The gate is held in upright position by any suitable means. I have shown latches 35 secured to the end gate by staples 36 and adapted to fit into keepers 37 secured to the 10 abutments 17. The latch just described is a device common in this connection.

This application is a division of my co-pending application Serial No. 183,877, filed 15 August 1, 1917, now Patent No. 1,268,547, issued June 4, 1918.

I claim:

1. In a drop end gondola car, the combination with the side walls and underframing of the car, of an end gate for said car 20 comprising a sheet metal panel formed with inwardly pressed corrugations and having its vertical edges bent at right angles to the main portion of the panel to provide rigidifying marginal flanges, an inverted channel secured to the top marginal flange of 25 said sheet, a channel secured to the lower edge of the gate, abutments for the vertical edges of the gate, and means for hinging the said gate to the underframing of the 30 car, comprising a U-bolt secured to the channel at the lower edge of the door, a staple secured to the underframing of the car a short distance back of said U-bolt, and a link connecting said U-bolt and staple.
2. In a drop end gate gondola car, the combination with the body of the car, of means on said car body providing abutments for the edges of the end gate, and an 35 end gate hinged to said body comprising a metal sheet formed with rigidifying corrugations, wooden filler members fitting into and lying lengthwise of said corrugations, and means extending transversely of said 40 filler strips for uniting said strips and to reinforce said metal sheet.
3. In a drop end gate gondola car, the combination with the body of the car, of means on said car body providing abutments for the edges of the end gate, and an 45 end gate hinged to said body comprising a metal sheet formed with rigidifying corrugations, members which fit into certain of said corrugations, boards which extend transversely of said corrugations and lie 50 against said members, and means for uniting said filling members and metal sheet to form a unitary end gate panel.
4. In a drop end gate gondola car, the combination with the body of the car, of 55 means on said car body providing abutments for the edges of the end gate, and an end gate hinged to said body comprising a metal sheet formed with rigidifying corrugations and provided with angularly dis-

posed reinforcing elements at certain of its 65 edges, and a wooden structure secured to said sheet, the edges of which are embraced by said angular reinforcing elements.

5. In a drop end gate gondola car, the combination with the body of the car, of 70 means on said car body providing abutments for the edges of the end gate, and an end gate hinged to said body comprising a metal sheet formed with rigidifying corrugations and provided with angularly dis- 75 posed reinforcing elements at its edges, wooden filler strips which fit into certain of said corrugations, and boards which extend across the end gate transversely of said corrugations and lie against said filler strips 80 with their extremities engaging the adjacent reinforcing elements, and means for uniting said boards, filler strips and metal sheet to form a unitary end gate panel.

6. In a drop end gate gondola car, the 85 combination with the body of the car, of means on said car body providing abutments for the edges of the end gate, and an end gate hinged to said body comprising a metal sheet formed with rigidifying corrugations 90 and provided with angularly disposed reinforcing elements at its edges, boards which extend transversely of said corrugations with their extremities engaged with the adjacent reinforcing elements, and means for 95 uniting said boards and metal sheet to form a unitary end gate panel.

7. In a drop end gate gondola car, the combination with the body of the car, of means on said car body providing abutments 100 for the edges of the end gate, and an end gate hinged to said body comprising a metal sheet formed with rigidifying corrugations and with flanges formed at two oppositely disposed edges, rigidifying, channel-shaped 105 elements secured to the other two edges of said sheet, and boards secured to said sheet and extending across said corrugations with their extremities engaged with said channel-shaped reinforcing elements.

8. In a drop end gate gondola car, the combination with the body of the car, of means on said car body providing abutments for the edges of the end gate, and an end gate hinged to said body comprising a 110 metal sheet formed with horizontally disposed corrugations and provided with rigidifying elements at its edges, filler strips in certain of said corrugations, and lining 115 boards secured to said filler strips and sheet 120 and disposed transversely of said corrugations with their extremities engaging certain of said rigidifying elements.

9. In a drop end gate gondola car, the combination with the body of the car, of 125 means on said car body providing abutments for the edges of the end gate, and an end gate hinged to said body comprising a metal

sheet formed with horizontally disposed corrugations and with angularly disposed flanges at its edges adjacent the ends of the corrugations, horizontally disposed channel-shaped reinforcing elements secured to the upper and lower edges of the sheet, filler strips in certain of said corrugations, and boards arranged transversely of the corrugations and secured to said sheet and filler strips with their extremities engaging the inner flanges of said channel shaped reinforcing elements.

CLARENCE W. COURT.
